UNITED STATES PATENT OFFICE.

JOSEPH STRACHAN, OF BROOKLYN, NEW YORK.

FOLDING RACK FOR SOLAR-PRINTING FRAMES.

SPECIFICATION forming part of Letters Patent No. 366,134, dated July 5, 1887.

Application filed February 11, 1887. Serial No. 227,318. (No model.)

To all whom it may concern:

Be it known that I, JOSEPH STRACHAN, of Brooklyn, in the county of Kings and State of New York, have invented a new and Improved 5 Folding Rack for Solar-Printing Frames, of which the following is a full, clear, and exact description.

This invention relates to a folding supporting frame or rack that is especially applicable 10 for use as a support for solar-printing frames, the parts being so arranged that they may be folded to occupy a minimum amount of space when not in use, and adjusted to a proper width to support the frame to be used in connection therewith, and also so that they may 15 be adjusted to extend outward in a horizontal plane, or at an angle thereto.

Reference is to be had to the accompanying drawings, forming a part of this specification, 20 in which similar figures of reference indicate corresponding parts in all the views.

Figure 1 is a side view of my improved supporting rack or frame, the parts being represented as they appear when placed in position 25 to support a printing-frame. Fig. 2 is a plan view of the supporting-rack, the parts being represented in full lines as they appear when adjusted for use and in dotted lines as they appear when folded for storage; and Fig. 3 is 30 a sectional end view taken on line $\alpha\alpha$ of Fig. 1, the clamping attachment being represented as it would appear when folded over upon the top of the main supporting-arms.

In constructing such a rack as the one forming 35 the subject-matter of this application, and illustrated in the drawings above referred to, I provide two main supporting-arms, 10 and 11, said arms being each formed with an upwardly-extending flange, 2. The arms 10 and 40 11 are united by centrally-connected rods 12, which said rods are formed with longitudinal slots 3, through which slots and the arms 10 and 11 there are passed studs or bolts 4, connection between the rods 12 being established 45 by means of a set-screw, 5, by means of which the rods are clamped together, so as to hold the arms 10 and 11 at a proper distance to properly support the printing-frame.

To the inner ends of the arms 10 and 11 there 50 are hinged folding strips 13, which carry extensible strips 14, these strips being preferably

made of sheet metal, and each leaf being provided with overhanging lugs or ears 6, within which the adjacent strip rides. The strips 14 are formed with longitudinal slots 15, through 55 which there pass bolts 16, that are carried by the strips 13, the two sets of strips 13 and 14 being clamped together by means of winged nuts 17, that engage the bolts 16. The strips 13 are formed with lugs or ears 7, between 60 which lugs or ears I mount forward braces, 18, said braces being pivotally connected to the lugs and arranged so that they may fold upward against the under side of the strip. The strips 14 are also formed with lugs or ears, as 65 shown at 8, and between these lugs or ears I mount rear braces, 19, which are also hinged to the lugs and arranged to fold upward against the under side of the strips in connection with which they are arranged.

To the flanges 2 of the arms 10 and 11, I 70 pivotally connect adjustable brace rods 20, which rods are each provided with an articulated foot, 21, and in order that the rods may be held in any desired position to which they 75 may be moved I provide each rod with a chain, 22, that may be caught upon a hook, 23, that is carried by its flange 2.

To the forward ends of the flanges 2, I hinge 80 stops 24, which may be moved to the position in which they are shown in full lines in Fig. 2, or folded back to the position indicated by dotted lines in said figure; and these stops serve to prevent the printing-frame proper from being moved too far outward or from 85 falling off of the supporting-rack.

Such being the general construction of my improved solar-printing frame-supporting rack, the operation is as follows: The set-screw 5 is loosened and the arms 10 and 11 are moved, 90 so as to provide for the introduction of the frame between the flanges 2. The set-screw is then tightened to clamp the rods 12 together. The stops 24 are moved to the position shown in full lines, and the strips 13 and 14 are adjusted, as indicated in Fig. 1, so as to bring the braces 18 and 19 to a position to bear closely against the window-frame casing, the two strips 13 and 14 being at this time clamped together by turning the winged nut 17 hard 95 down. The braces 20 are adjusted so as to support the rack at the desired angle, or in a 100

horizontal plane, as indicated in Fig. 1, which adjustment, it will be readily understood, may be brought about by bringing proper links of the chains 22 into engagement with the hooks 23, the parts being so adjusted that the printing-frame proper may be slid out upon the arms 10 and 11. When the rack is not in use, the strips 13 and 14 and their connections are folded over to the position in which they are shown in dotted lines in Fig. 2. The set-screw 5 is loosened and the two arms 10 and 11 are brought together, the connection between said arms and the rods 12 being such as to permit of this collapsing.

15 Such a rack as the one above described is cheap, convenient, and durable, and when not in use may be adjusted so as to occupy a very small space, as the parts may be folded to the positions in which they are shown in Fig. 2, and as the direct support for the printing-frame may be adjusted so as to extend from the window at any desired angle the printing may be carried on at all times of the day, irrespective of the position of the sun.

25 Although I have described my invention in connection with a solar-printing frame, it will of course be understood that the rack could be used to support any other object which it is desired to place outside of the window.

30 Having thus fully described my invention, I claim as new and desire to secure by Letters Patent—

1. The combination, in a folding rack, of

supporting-arms, connecting-rods pivoted together and connected to the supporting-arms 35 by a pivotal and sliding connection, and an adjustable clamping device on the inner ends of the supporting-arms, substantially as herein shown and described.

2. In a folding rack, the combination of 40 supporting-arms provided with flanges and adjustably connected together, braces hinged to the supporting-arms, and an adjustable clamping device hinged to the inner ends of the supporting-arms, substantially as herein 45 shown and described.

3. The combination, with the arms 10 and 11, formed with flanges 2, of rods 12, formed with longitudinal slots 3 and connected to the arms 10 and 11 by studs or bolts 4, a set-screw 50 arranged to connect the rods, adjustable clamping attachments hinged to the arms, braces 20, and a means for adjusting the position of the braces, substantially as described.

4. The combination, with the arms 10 and 11, formed or provided with flanges 2 and adjustably connected, of braces 20 and a means for adjusting the position of the braces, strips 13, hinged to the arms 10 and 11, strips 14, adjustably connected to the strips 13, and 55 braces 18 and 19, carried by said strips 13 and 14, substantially as described.

JOSEPH STRACHAN.
